UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

OPERATOR'S SELECTIVE RINGING-KEY FOR TELEPHONE SYSTEMS.

No. 887,260.

Specification of Letters Patent.

Patented May 12, 1908.

Application filed November 15, 1904. Serial No. 232,857.

To all whom it may concern:

Be it known that I, RAY H. MANSON, a citizen of the United States, residing at Elyria, in the county of Lorain and State of Ohio, have invented certain new and useful Improvements in Operators' Selective Ringing-Keys for Telephone Systems, of which the following is a specification, reference being had therein to the accompanying drawing.

My invention relates to telephone exchange systems, and particularly to circuits and apparatus used therein and in connection therewith for the purpose of serving more than one party over one exchange line, or party line, and for selectively signaling any one party to the exclusion of others on the same line.

Briefly stated, my invention resides in a four party selective key and its connections, together with line arrangements coöperating therewith.

Heretofore, according to the best practice, party lines equipped for selective ringing have had four parties on the line, either with their ringers bridged and adapted to respond to currents of different frequencies, or having the ringers grounded from opposite sides of the line and adapted to respond to currents of opposite direction. Calling keys have been provided comprising double elements, first, the ordinary ringing key which puts generator to line and severs the cord circuit so as not to ring back, and second, a special selective key-set usually with four buttons each corresponding to one subscriber's position on the line and each adapted to connect a calling generator to the principal key contacts in the proper manner to call the corresponding station. A catch has been provided, or its equivalent, for holding down the key last depressed, so that the operator can ring again if the subscriber does not at first answer, the necessity for remembering which key was used being thus obviated.

It is the object of my present invention to improve keys of this general type and their circuits, so as to simplify them and decrease the chances of trouble. In the older type of keys there are many springs and many contacts through which the talking circuit or ringing circuit must pass, some of these contacts being individual to each selective key,

and as in all series contacts, trouble with any one would disable the circuit. Moreover, the provision of a separate ringing key for use after selection has been made necessitates an additional operation on the part of the operator, with consequent waste of time. I simplify the key by doing away with this main ringing key, and performing its function incidentally in the use of the selective keys. Again, in the present type of keys where a mechanical catch is employed for the selective keys, if it should happen that more than one key becomes caught at the same time the latch must be thrown back by means separate from the keys themselves, which requires either a separate projecting arm or lever accessible from the top of the key shelf, or that the shelf be lifted up or opened to get at the key from beneath. According to my present invention, I provide means whereby, after a key is depressed, it is held by the latch in an intermediate position, and by further depressing it the latch will be released, thereby releasing any other key which it is not desired to hold.

The primary object of the multiplicity of series contacts in some of the older keys, is to open the generator circuit back of any individual or selective key, to prevent sending ringing current from several generators to line, if more than one plunger, or button, is accidentally depressed at the same time. In some systems, this trouble would cause more than one bell to ring on the line. By a simple modification of my present key, which I shall describe, the same series arrangement can be employed for cutting off, without the introduction of more than two contacts in the metallic talking circuit. This precaution is not necessary in a harmonic system employing different frequencies to ring bridged bells. The cutting down of the number of ringing springs from twenty-four in old standard keys to thirteen in my new key, not only simplifies the circuits and reduces the cost of manufacturing, but reduces the chances for trouble and the cost of maintenance. The last two points are vital from the operating standpoint, the first two from that of the manufacturer.

In constructing my key, each selective plunger is provided with two, or at most, three, springs, and upon the end of the frame the usual ringing key contacts are mounted,

being actuated by a projecting finger on the latch plate, so that when any selective key is depressed to the fullest extent, the main ringing key is also actuated. The main ringing key contacts are located on the end of the frame, and the latter is mounted on the key shelf with this end to the front. As all the ringing key contacts are visible at the front ends of the frames, and as these are the only contacts in the talking circuit, it follows that all talking circuit contacts can be inspected by merely lifting up the key shelf.

The release frame, or latch plate, is actuated by a flat spring which also serves as a lock to hold it in position. The frame can be removed by pressing this spring out of engagement with a small lug located on the frame, allowing the latter to be moved to one side to clear its pivot.

My invention is illustrated in the accompanying drawings wherein

Figure 1 is a side view of my improved selective key with parts in section. Fig. 2 is a similar view from the other side to that shown in Fig. 1. Fig. 3 is an end view showing the main ringing key contacts, and Fig. 4 is a transverse section through one of the plungers in Figs. 1 or 2. Fig. 5 is a diagram of the key circuit for the key as shown in the preceding figures, while Fig. 6 is a diagram of a slightly modified circuit having series cut off keys. Fig. 7 is a jack and line circuit diagram, showing four stations with bridged bells.

Referring to Figs. 1, 2, 3, and 4, A is the top plate of the key frame, which I have shown faced with hard rubber on a metal underplate a. This top plate is let into the top of the key shelf transversely thereto with the end A' in front, and the frame B projecting down through the shelf. This frame consists of side members or posts b, b', secured at their upper ends to the top plate a, and connected at their lower ends by the bar B', which is composed of a body of hard rubber b², faced with metal side plates b³ secured together by screws b⁵ extending through from one plate to the other. The rubber strip b² is drilled at b⁶, b⁷, b⁸ and b⁹ to receive the lower ends of the plungers c, c', c², and c³, respectively. The upper ends of these plungers work in corresponding openings in the top plate, each being fitted with a push button C, C', C², or C³. These buttons may be of different colors, if desired. About midway of its length each plunger has a portion of increased diameter, with a cross slot c⁴ extending through it. In each of these slots a friction roller is pivoted, the roller being of hardened fiber, and the pivot a case hardened steel screw, whose tip end serves as a catch pin to hold the plunger down, as will be explained hereafter. These screws are shown at c⁵, and above them are shown twin screws c⁶, somewhat longer than the screws c⁵ and

whose tips also serve to control the latch plate P. Each plunger is normally thrown up into inactive position by a coil spring c⁷.

The rubber strip b² has transverse slots cut in it corresponding to and slightly removed from the openings b⁶, etc., and in these slots are set the springs s, s', with interposed slips of insulation, s². An overlying strip of insulation is then laid along the side of the main strip, and the metal side strip b³ placed upon this, holding the springs all in place. These springs extend up in pairs corresponding to the plungers, the one s in each case constituting an anvil upon which its companion s' comes down when its plunger is depressed. The upper end of this companion spring is formed with a projecting portion s³ normally lying below the friction roller of its plunger, which is partly cut away so as not to make contact with the spring. The upper end of the spring extends over and rests upon the roller at all times.

In order that the plungers may not rotate in their bearings, but may keep the rollers and the pins in line with their coöperating parts, a guide plate G is provided secured to the underside of the top plate by lugs g, and having slots g' in which the pins c⁶ work up and down.

Pivoted to the end post b by pivot-pins p, is the latch plate P, having a ringing finger p' extending out from one end of its body and bent over, as shown at p² in Fig. 3, so that its extremity will engage the ringing key springs. The plate is cut away at p³, p⁴, p⁵, and p⁶ to form openings which will take in the pins c⁵ when the plungers are depressed. The upper edge of these openings at p⁷ engages with the pins when they are down, and the cam surface p⁸ is acted upon by the pins as they pass down to throw the plate P back. It is to be observed that the pins c⁵ will latch under the edge p⁷ before the plungers reach the lowermost position, and that a further movement of any plunger brings the pin c⁶ against the cam-plate p⁸ to force the plate P farther back than before. This extreme movement of the plate throws over the extension finger p² far enough to actuate the ringing key R. This main controlling key R comprises the springs r, r', r², r³, and r⁴ all set into the end of the rubber strip b², and held in place by the screw b⁵⁰. The springs r, and r³ are stiffened by an intermediate strip of insulation, so as to form contact anvils with which coöperate the other springs. Springs r² and r⁴ are connected by an insulating stud r⁵, whose head lies on the outside of the spring r² and so insulates it from the finger p². When the finger p² is moved to the right, as shown in Fig. 3, the springs r', r² and r³, r⁴ are separated, spring r² being then connected with the generator spring contact r. In other words, the two sides of line are broken, and the generator is connected to the forward end of one of

them. The plate P is pivoted on a line near its lower edge upon the pins p , and it will be noted that these pins relatively lie upon the same sides of the two posts b , so that unless the plate were held against those posts it would come off its pivot. To hold it in position, and at the same time, to normally retract it, as shown in Figs. 3 and 4, I provide the spring P' , whose lower end p^{10} presses outwardly against the lower edge of the plate P, and prevents a longitudinal movement thereof (or end play) by engaging with a small inturned finger p^9 formed up on the edge of the plate. The upper end of the spring P' is screwed or otherwise secured to the post b , and it is evident that by merely pushing in the spring to clear the finger p^9 , the plate P may be shifted endwise and removed.

Referring to the circuit diagrams Figs. 5, 6, and 7, the first two show cord circuits with keys such as I have described, applied thereto, and Fig. 7 shows a line circuit to coöperate therewith. I will briefly describe the latter first. The line wires 5 and 6 pass to contact springs or armatures u controlled by the cut-off magnet U, being normally connected to line signaling devices. The magnet winding is connected to the sleeve j of the jack J, whose spring j' goes to one contact, and the sleeve j to the other of a pair closed to line by the magnet U when the latter becomes energized. Bridged across the line are four ringers Q, Q', Q'', and Q'', each in series with a suitable condenser, and all supposed to be located at different stations.

Referring to Fig. 5, which is my preferred form of key-circuit, 1 and 2 are the cord conductors of an operator's set, with extensions 3, 4 through the ringing key R to the plug T, the latter having tip and sleeve contacts t and t' to coöperate with the two contacts j' and j of the jack. In the ringing key, the springs r^2 , r^4 normally complete the cord circuit for talking purposes through the contacts r' , r^3 . The contact r is connected to a generator or battery N, through a resistance r^5 , in order to furnish current through the sleeve of the plug and the sleeve of the jack to the magnet U to energize the latter while ringing, ringing current itself not always being suitable for this purpose, as it permits chattering and uncertainty of contacts. The springs s are the moving contact springs of the individual selective keys C, C', etc. When one of these is moved over against its contact s it connects the individual generator M between the ground and the conductor 3, thence to the tip t , and when the plug is in a jack, through the spring j' and armature u , over line wire 5 to, say, the first ringer Q for operative purposes, back by line wire 6 through the sleeves t' and j to conductor 4, spring r^2 , point r , resistance r^5 , battery N,

ground, and back to the generator M. The lamp resistances l prevent trouble from short circuiting when more than one plunger is accidentally depressed.

Referring to Fig. 6, I have shown the same number of generators, the same lamp resistances, and the same ringing key connections, but instead of connecting all the springs s' in parallel along the conductor 3, I connect them in series through back contacts s^{10} , with a series of short connecting links 8, 9, 75 and 10, so that if the plungers C', C'', or C''' are used they will cut off all previous plungers in the series, and make it practically impossible to put two generators to line at the same time. The conductor 3 in this case is 80 connected to the last spring only, and it should be specially noted that even with this circuit I have only the two contacts at r' , r^3 in the metallic talking circuit.

In operation, my key mechanism works as 85 follows: When any plunger is depressed its projecting pin c^5 first strikes the cam surface p^8 on the plate P and throws the latter back against the spring P' . The movement continues until the pin c^5 has passed down under 90 the edge p^7 , all other pins in the meantime having been released if any were caught. The spring s' has been forced against its companion s by this movement of the plunger, and so remains until the latter is released, 95 when the roller c^{10} is permitted to move up when the pin c^5 rests against the edge p^7 to separate the springs, but still retain the key in the position shown at C' in Fig. 1, as an indication to the operator of the line called. 100 In ringing, the operator presses the key all the way down, and in so doing the pin c^5 comes against the cam p^8 , and carries over the finger p^2 to work the controlling key R and break the cord circuit, as before, described. 105 When the key is released, the continuity of the circuit is restored automatically.

Most of the features of my improved key can be applied to existing forms of key, notably the releasing device consisting of the second pin c^6 acting on the cam p^8 . If more than one key becomes caught by accident, or for any other reason it is desirable to force back the latch plate, it is only necessary to push down one key to its final limit, and by 110 releasing the key very quickly it is even possible to prevent catching itself, although usually I adjust the keys to prevent this, certainty of latching being desirable.

I am quite well aware that changes and 120 modifications may be made as to details in the apparatus in circuit presented herewith, and I therefore wish it understood that I do not limit myself to the specific form described, but wish to include all such modifications and changes as do not depart from the spirit of the invention.

Having thus described my invention, what

I claim and desire to secure by Letters Patent is:

1. In an operator's key, the combination with a suitable framework having a top plate, of a plurality of plungers adapted to reciprocate through said top plate, each plunger having an enlargement beneath the top plate provided with a suitable slot, a friction roller in said slot, a contact spring adapted to engage said roller, and a plate secured to the lower face of said top plate with a body portion extending parallel to the plungers, slots cut in said plate parallel with the axes of the plungers, and projections on the plungers so set with respect to the axes of the friction rollers as to maintain the latter in proper relation with their springs during the reciprocating movement of the plungers, substantially as described.
2. In an operator's key, the combination with a suitable framework, of a plurality of plungers mounted to reciprocate therein, switch springs mounted beside the plungers, insulating rollers carried by the plungers in slots therein to operate said springs, said rollers secured in the slots by means of suitable screws passing through the rollers and the plungers, the ends of said screws extending beyond the plungers on one side, means to engage the projecting ends of the screws to retain the plungers out of normal position when they have been operated and pressure is removed therefrom, together with additional projecting pins attached to the plungers at points above said screws and adapted to release the retaining means in further movement of the plungers, substantially as described.
3. In an operator's key, the combination with a suitable framework, of a plurality of key plungers mounted to reciprocate therein, a set of switch contacts actuated by each plunger, and a pivoted latch plate adapted to retain the last one of said plungers to be operated, out of its normal position, after its switch contacts have been operated and to permit any other retained plunger to return to normal, together with means carried by each plunger and apart from the latch mechanism, to release said latch plate from all the plungers, including the one actuated, substantially as described.
4. In an operator's key, the combination with a frame, of a plurality of selective plungers therein, independent of any circuit connections, a latch plate therefor adapted to lock the actuating plunger in an intermediate position, a controlling key common to all the plungers, and means carried by the latch plate for actuating said controlling key and to release all plungers previously depressed, said latch plate controlled by any one of said plungers, substantially as described.
5. In an operator's selective key, a frame, a plurality of plungers mounted therein, generator contacts controlled thereby, a set of contacts controlling the continuity of one or both of the main conductors to which the key is connected, a pivoted plate extending into proximity to all the plungers and having a portion adapted to engage and actuate the said set of continuity springs, together with means carried by each plunger in its movement to move said plate and to actuate the continuity springs said means coöperating with said plate to lock the plungers, substantially as described.
6. In an operator's selective key, the combination of the frame, a plurality of plungers adapted to reciprocate in said frame, generator springs controlled by each plunger, continuity springs separately mounted upon the key frame, a latch plate adapted to be engaged by and to hold down any plunger when moved, and a projection on said latch plate extending into position to engage said continuity springs to move the same upon the operation of a plunger, substantially as described.
7. In an operator's selective ringing key, a frame, a set of reciprocating plungers therein, contacts controlled thereby, a latch plate extending along the frame and adapted to engage projections on the plungers, contact springs mounted on the frame and engaged by the plungers, and means detachably holding the latch plate in position but permitting the withdrawal of the same lengthwise of the frame without disturbing any contacts and without disturbing adjacent keys or key wiring, substantially as described.
8. In an operator's selective key, a frame, a set of reciprocating plungers, a latch plate for the plungers pivoted upon pintles having their free ends pointed in the same direction, a retractile spring for said latch plate adapted to turn it upon the pintle and at the same time normally to hold it against end play thereon or disengagement therefrom, substantially as described.
9. In an operator's selective key, the combination of the frame, a plurality of plungers adapted to reciprocate in said frame, generator springs controlled by each plunger, continuity springs mounted on the end of the key frame in planes extending lengthwise of such frame, a latch plate adapted to be engaged by and to hold down any plunger when depressed and means operated by any of such plungers for controlling such continuity springs.

In testimony whereof I affix my signature in presence of two witnesses.

RAY H. MANSON.
